UNITED STATES PATENT OFFICE

2,205,085

RAILWAY SLEEPING CAR

David A. Crawford, Golf, Ill., assignor to The Pullman Company, Chicago, Ill., a corporation of Illinois

Application November 3, 1938, Serial No. 238,537

14 Claims. (Cl. 105—316)

This invention relates to conventional railway sleeping cars of the type providing sections each having upper and lower berths for individual occupancy and has particular reference to such cars when offering these accommodations as "single occupancy sections."

The principal object of the invention is the provision of dressing space in "single occupancy section" accommodations without increasing the overall dimensions of the individual sections.

A further object of the invention is the provision of a "single occupancy section" with enclosed dressing space and a seat in the dressing space.

Another object of the invention is the provision of a "single occupancy section" bed which is hinged to provide a portion that may be raised to provide standing space for dressing and capable of operation from inside or outside of the section.

An important object of the invention is the provision of a portable washbasin which may be removably mounted on the side wall of a section by means of the usual table slots and having supplemental supporting means and equipped with separate means for supplying hot and cold water.

Other and more detail objects are attained by the arrangement illustrated in the accompanying drawings, in which—

Fig. 1 is a cross-sectional view through a railway car equipped with the invention and illustrating the bed in raised position for dressing, on one side of the view, and the section seats made up for day occupancy on the other side of the view;

Fig. 2 is a side-elevational view of the seat arrangement with parts broken away better to illustrate the type of seats used and their method of operation;

Fig. 3 is a view similar to Fig. 2 but illustrates the bed made up for night occupancy with one seat cushion removed to provide standing room for dressing when the bed is in the raised position as indicated in dotted lines;

Fig. 4 is a transverse, sectional view taken on the line 4—4 of Fig. 3;

Fig. 5 is a disassembled perspective view of the hinged mattress-supporting panel and appurtenances;

Fig. 6 is a general perspective view of the "single occupancy section" with dressing space made up ready for use and showing the portable washstand in position for use;

Fig. 7 is an enlarged sectional view showing

the application of the portable washstand to the side wall and disposed ready for use;

Fig. 8 is a perspective view of the washstand removed from the side wall and closed up ready for storage; and

Fig. 9 is a perspective view of the separate hot and cold water container.

In conventional sleeping cars of the type contemplated for application of this invention—having a plurality of sections upon opposite sides of a central aisle—each section is provided with confronting seats for day use which are convertible into lower berths for night occupancy, and each section also has an upper berth which, in the present invention, is kept closed at all times but is used for the storage of all bedding for the section, including mattresses for the upper and lower, pillows, blankets and the like. When the confronting seats are converted into a lower berth in an ordinary "single occupancy section," the occupant, to dress, must stand in the aisle of the car between the edge of the berth and the curtains, but, in the present invention, standing room, together with a seat and a large mirror for dressing, is provided in the section itself, thereby affording the utmost privacy and comfort.

The "single occupancy section" has been improved by the use of this invention by hinging the bed approximately in the center, whereby a portion of the bed may be folded upwardly to a vertical position, leaving the cleared space available for dressing, and, when ready to retire, the occupant merely lowers the bed from inside the section or, if desired, the porter can do this from the aisle of the car outside the berth curtains. The dressing space is made available by removing one of the seat cushions and storing it in the closed upper berth. The additional dressing space increases the comfort of the section accommodation—whether used by one or two persons. The folding device takes up no room in the accommodation and in no way affects the softness, resilience or sleeping qualities of the bed. In fact, the sleeping qualities of the bed are actually improved, since the upper berth in this invention is not utilized for sleeping and the upper berth mattress therefore is placed in the lower berth, with the usual lower berth mattress, for the greater comfort of the occupant. The arrangement is applicable to and primarily intended for existing equipment, but is equally adapted to use in new equipment.

In the drawings, 10 represents a railway car having a plurality of sections 11 defined by partitions 18—each having an upper berth 12 and a

pair of confronting seats 13. The seats are adjustable to several positions for the daytime comfort of an occupant and at night are adapted to form a support for the mattress. The seats each 5 comprise a seat cushion 14, a back cushion 15 and a headrest cushion 16 extending between the side wall of the car and the respective seat ends 17. In ordinary practice in converting the seats into a bed, the seat cushions 14 of confronting 10 seats slide together to abut at the center of the section, and the back cushions 15 drop from their usual vertical position to a horizontal position behind the respective seat cushions, thereby to form a continuous mattress support the full 15 distance between section partitions 18; but for the purpose of this invention one of the seat cushions 14 is removed when the berth is made ready for night occupancy and stored in the closed upper berth, as shown in Fig. 1—the function 20 and operation of the seats otherwise remaining the same. To provide a base for the mattress 19 across the space existing between the remaining extended seat cushion 14 and the lone horizontal back cushion 15, a relatively thin but rigid 25 panel 20 bridges the opening and affords a positive support for the otherwise unsupported portion of the mattress. The panel 20 is provided with a hinge 21 approximately in the center thereof adjacent the edge of extended seat cushion 30 14—permitting the panel to fold upwardly. The panel 20 is hinged off center with respect to the center of the section so that the portion spanning the opening created by removal of the one seat cushion will be supported in the horizontal position 35 both on the lone back cushion 15 on one side of the opening and on the other side of the opening on the remaining seat cushion 14 and not dependent wholly on the hinge for its support on that side, as best shown in Fig. 3, and in the 40 raised position of the hinged portion of the panel and the mattress they will be wholly supported on the remaining seat cushion as shown in Fig. 6.

The foot of the mattress is removably secured to the panel 20 by means of strap 22 passing 45 thereabout and removably attached to the panel by buckles 23 engaging rings 30 at opposite sides thereof and having a fastening 24 for ready securing of the strap about the mattress at the time of making up the bed; and, if desired, the strap 22 might be used in multiple. The strap 50 is passed about the bed after it is made up and serves to help hold the bedding in place when in the vertical position. The fastening 24 is also useful in that it permits release of the strap 22 by the occupant, at the time of getting in bed, 55 for greater comfort and to avoid any binding feeling about the feet. The mattress, with its supporting hinged section of panel 20, may be folded to the vertically disposed position indicated in Fig. 6, thus exposing the dressing space 25 and cushion 15 which may be utilized as a seat for dressing purposes.

The mattress and hinged section of the panel 20 are raised to their vertical position by means 60 of ring 26 secured to strap 22 providing a handhold for lifting them and are held in that position by a safety strap 27 removably secured to one of the section partitions 18 by means of a clamp 28. The strap 27 has a safety catch 29 for engagement 65 with a ring 29^b secured to the hinged section of the panel 20 and which may readily be attached by the occupant of the section and which is easily detachable by merely turning the securing hook 29^a to release position—the hook normally being held in locked position by tension on the

strap due to the application of such force in line with the pivotal point of the hook 29^a. To raise the mattress, the occupant of the section stands between the edge of the bed and the berth curtains 31 enclosing the section, grasps the ring 26, 5 raises the mattress to vertical position and engages catch 29^a in ring 29^b and secures it; but, if desired, the mattress may be raised by the car porter from the aisle of the car outside of curtains 31 without the necessity for his entering the 10 section. Cable 32 is suspended over pulley 33 supported from the curtain-supporting rods 34 by means of hook 35 engaging both the rod 34 and arm 36, as best shown in Fig. 1, and one end of the cable hangs on the outer side of the berth 15 curtains to be operated by the porter upon the request of the occupant of the section, and the other end hangs on the inner side of the curtains and is provided with a snaphook 37 for engagement with a lifting ring 38 secured to the hinged 20 section of the panel 20. After the hook 37 has been engaged in the ring 38, the exertion of tension on the cable 32 outside the berth curtain causes the mattress and hinged portion of the panel to assume the vertical position where they 25 are held by catching hook 39 on cable 32 under the edge of seat end 17. The hook 39 is bound with non-abrading material to avoid scuffing the seat end and is shaped properly to engage beneath the seat end as shown. As a safety measure, the 30 occupant of the section then may secure the safety strap 27 by means of the catch 29, whereby, if the hook 39 should accidentally be disengaged from beneath the seat end, the bed cannot fall until it is desired that it shall be lowered. 35

In raising and lowering the bed, the headrest 16, as best shown in Fig. 3, must be raised to the position indicated in Figs. 3 and 6 to provide clearance for the swinging end of the bed, and a separate and detachable shelf 87 is supported 40 thereon for the accommodation of the personal belongings of the occupant or for baggage or the like. The shelf 87 is made of fabric and is removably secured to the headrest cushion 16 by means of straps 88. An adjustable strap 90 45 from the shelf 87 also extends upwardly and is secured to the curtain-supporting rod 34 by means of hook 89. A plush boot 82 having a reinforcing frame 83 is utilized to cover the extended portion of the adjustable seat frame 84 and extends all the way to the floor to prevent a person's 50 foot from coming under the seat frame with the consequent bumping of the leg thereon, and is secured in place by means of a buttonhole 86 engageable over the adjustable seat-securing knob 85. 55

The underside of the hinged panel 20 is provided with a mirror-like reflecting surface 40 which, in the vertical position of the parts, provides for the convenience of a person using the 60 space 25 for dressing. The panel 20 is prevented from becoming displaced longitudinally of the berth by means of downwardly hinged flap 41 which is adapted to be inserted downwardly between back cushion 15 and the section partition 65 18 at the head of the bed, as best shown in Fig. 3, whereby the panel is prevented from slipping upon manipulation of the hinged section. Laterally extending hinged flaps 42 prevent displacement of panel 20 transversely of the berth by providing close engagement with the side wall of the car and the inner side of the seat end 17 and are hinged to fold in an upward direction to insure 70 their being horizontal at all times in the operative position of the panel for proper engagement 75

with the side wall and seat end. The flaps 41 and 42 serve to maintain the panel 20 and associated mattress in proper position for the efficient functioning of the hinged portion. The panel 20, in 5 the daytime, when the section is made up for day occupancy, is folded up and stored in the upper berth 12 together with the bedding and curtains and other paraphernalia used in night operation, and the seat cushion 14 then restored to its normal 10 position in the seat. The upper berth 12 is maintained in the closed position at all times during the realization of this invention and is utilized merely for storage purposes, and the mattress ordinarily used for the upper berth is combined 15 with the lower berth mattress for the greater comfort of the user of the "single occupancy" section."

As best shown in Fig. 6, facilities are provided whereby the occupant of each section is afforded 20 a private individual washbasin with hot and cold water. The washbasin 45 is removably mounted on the side wall of the car by means of retaining bracket 46 which, as best shown in Fig. 7, enters the usual table slot bracket 44 with which it interlocks by means of the lip 47 in such manner 25 that the outer portion of the washbasin must be lifted upwardly before the retaining member 46 can be removed from the slot bracket 44 whereby, since all forces on the basin normally are in a downward direction, any chance of its accidentally becoming displaced is avoided. The washbasin is afforded a three-point support by means 30 of folding legs 48 hingedly mounted on the underside of the basin adjacent the outer portion thereof, as at 49, and resting on the usual heater pipe cover or footrest 50 and is thereby rendered more stable in use. The legs 48 are hinged at 51 to fold into the position indicated in Fig. 8, where they are held by means of spring clips 52 when 35 not in use. The hinge 51 is disposed to one side of the center of the respective legs 48, and a spring 53 connects the two hinged sections of each leg in such manner that in the operative position a force is exerted tending to hold the legs in extended position, and likewise, in their collapsed 40 condition, a force is exerted tending to maintain the legs in folded position due to the fact that the spring is so mounted as to exert its force beyond dead center in the two such extreme positions 45 of the legs.

The washbasin 45 comprises the bowl 55 having a drain opening 54 with removable plug 56 and the rim structure 57 to which the bowl is secured by welding, as best illustrated in Fig. 7, and is 55 provided with a cover 58 having a mirror surface 60 and hinged to the rim structure at 59 in position to be raised, as shown in Fig. 6, for use of the washbasin and mirror. Removably secured to the drain opening 54 is a flexible receptacle 61 for receiving waste water drained from the bowl 55. The receptacle 61 comprises an expandable bellows-fold, moisture-proof container secured to the drain 54 by means of a threaded connecting member 62 which is rotatably mounted 60 in bearing 63 about the drain and provided with a knurled surface 64 for turning the member 62 to release the receptacle 61 for emptying. The flexible receptacle is supported in an enclosing member 65 hinged to the rim structure adjacent 65 the outer portion, as at 66, and having a receptacle retaining flange 67 and side walls 68 having flanges 69 which, in the operative position of member 65, rest upon the underlying flange 70 of the rim structure to support the member 65 in 70 such operative position. After the receptacle 61

has been emptied and restored to its normal position secured to the drain 54, the member 65 is folded upwardly—collapsing the receptacle 61 and causing the side walls 68 to enter the space between the bowl 55 and rim structure 57, as indicated in Fig. 8. The retaining bracket 46 is secured to the back wall 71 of the rim structure in a position to locate the washbasin with respect to the adjacent upright mattress, as desired, and is flanked on either side by rubber bumpers 72 secured to the wall 71 by screws 73 and which engage the side finish of the section to prevent any possibility of shifting or pivoting of the basin about the bracket 46. The supporting legs 48 are provided with adjustable extensions 78 to compensate for any variations in the dimension between the table slots 44 and the footrest 50 in the various sections.

Hot and cold water are provided in the section by means of the portable container assembly 75 20 which comprises the holder 74 having the bail 76 for ready handling and which also serves to keep the individual hot and cold water containers 77 in place. The containers 77 are of similar construction and removably mounted in the holder 25 74 for filling purposes, but are retained in the holder by the user and the hot or cold water poured from the respective spouts 79 as desired—the air vent 81 in each container permitting ready 30 flow of the water. Handles 80 permit ready 35 handling of the individual containers. In practice, both the container assembly 75 and the washbasin 45 are stored in the porter's locker at the end of the car, and when they are called for by the occupant of a "single occupancy section" 40 35 the porter fills the containers 77 with hot and cold water, respectively, and brings them to the section and installs the washbasin on the side wall—then leaving the occupant to perform his ablutions in privacy, after which he removes the 45 receptacle 61 and empties the waste water receptacle 61 and returns them to storage.

From the foregoing, it will be seen that the conventional sleeping car accommodation has 45 been improved by the use of this invention virtually to the status of a room and offers private, fully-enclosed dressing space within the section and permits either standing or sitting, with the convenience of a mirror for dressing, with portable washing facilities supported by the existing 50 table brackets, and provides a folding bed easily manipulated either by the occupant or by an attendant from without the section and in which the folding device takes up very little room in the section either in operative positions or collapsed 55 storage condition.

What is claimed is:

1. In a railway car having a section, confronting seats in the section each having a back cushion and a seat cushion convertible jointly to form 60 a mattress support, a mattress on said cushions, dressing space in said section formed by removal of one of said seat cushions, and a rigid panel supported on said remaining cushions having a hinged portion supporting said mattress over said 65 dressing space and movable with said mattress to a position to expose said dressing space.

2. In a railway car having a section, confronting seats in the section each having a back cushion and a seat cushion convertible jointly to form 70 a mattress support, a mattress on said cushions, dressing space in said section formed by removal of one of said seat cushions, and a rigid panel supported on said remaining cushions having a hinged portion bridging the space between the 75

- remaining seat cushion and the lone back cushion to support said mattress and movable with the mattress to a position to expose said dressing space, said lone back cushion providing a seat in said dressing space when exposed.
3. In a railway car having a section, confronting seats in the section each having a back cushion and a seat cushion convertible jointly to form a mattress support, a mattress on said cushions, dressing space in said section formed by removal of one of said seat cushions, and a rigid panel supported on said remaining cushions having a hinged portion bridging the space between the remaining seat cushion and the lone back cushion to support said mattress and movable with the mattress to a vertical position to expose said dressing space, and detachable means for securing said mattress and hinged portion of the panel in vertical position.
- 20 4. In a railway car having a section, confronting seats in the section each having a back cushion and a seat cushion convertible jointly to form a mattress support, a mattress on said cushions, dressing space in said section formed by removal of one of said seat cushions, and a rigid panel supported on said remaining cushions having a hinged portion bridging the space between the remaining seat cushion and the lone back cushion to support said mattress and movable with the mattress to a vertical position to expose said dressing space, means securing said mattress to the hinged portion of said panel, and means for releasing said securing means.
- 35 5. In a railway car having a section, confronting seats in the section each having a back cushion and a seat cushion convertible jointly to provide a mattress support, a mattress on said cushions, dressing space in said section formed by removal of one of said seat cushions, and a rigid panel supported on said remaining cushions having a hinged portion bridging the space existing between the remaining seat cushion and the lone back cushion to support said mattress and movable with the mattress to a vertical position to expose said dressing space, and means for moving said hinged portion and mattress to vertical position.
- 50 6. In a railway car having a section, confronting seats in the section each having a back cushion and a seat cushion convertible jointly to provide a mattress support, a mattress on said cushions, dressing space in said section formed by removal of one of said seat cushions, and a rigid panel supported on said remaining cushions having a hinged portion bridging the space existing between the remaining seat cushion and the lone back cushion to support said mattress and movable with the mattress to a vertical position to expose said dressing space, means for moving said hinged portion and mattress to vertical position, and means for securing said portion and mattress in vertical position.
- 55 7. In a railway car having an aisle, a section, confronting seats in the section each having a back cushion and a seat cushion convertible jointly to provide a mattress support, a mattress on said cushions, dressing space in said section formed by removal of one of said seat cushions, and a rigid panel supported on said remaining cushions having a hinged portion bridging the space existing between the remaining seat cushion and the lone back cushion to support said mattress and movable with the mattress to a vertical position to expose said dressing space, means inside the section for moving said hinged portion and mattress to vertical position, means for moving said hinged portion and mattress to vertical position and securing them from said aisle, and means inside said section for securing said hinged portion and mattress in vertical position.
- 60 8. In a railway car having an aisle, a section, confronting seats in the section each having a back cushion and a seat cushion convertible jointly to provide a mattress support, a mattress on said cushions, dressing space in said section formed by removal of one of said seat cushions, and a rigid panel supported on said remaining cushions having a hinged portion bridging the space existing between the remaining seat cushion and the lone back cushion to support said mattress and movable with the mattress to a vertical position to expose said dressing space, means for moving said hinged portion and mattress to vertical position and securing them from said aisle, and means inside said section for securing said hinged portion and mattress in vertical position.
- 65 9. In a railway car having a section defined by partitions, confronting seats in the section each having a vertical back cushion and a horizontal seat cushion, said seat cushions being movable to abutting relation at the center of the section and said back cushions to horizontal positions behind said seat cushions to provide a continuous mattress support between partitions, a mattress on said cushions, dressing space in said section formed by removal of one of said seat cushions, and a rigid panel supported on said remaining cushions having a hinged portion bridging the space between the remaining seat cushion and the lone back cushion to support said mattress over the dressing space and movable with the mattress to a vertical position to expose said dressing space, said rigid panel having a hinged flap engageable between one of said horizontal back cushions and a partition to prevent longitudinal displacement of the panel.
- 70 10. In a railway car having a side wall, a section in said car defined by partitions extending from the side wall, confronting seats in the section having seat ends defining the width of the section, said seats each having a vertical back cushion and a horizontal seat cushion, said seat cushions being movable to abutting relation at the center of the section and said back cushions to horizontal positions behind said seat cushions to provide a continuous mattress support between partitions, a mattress on said cushions, dressing space in said section formed by removal of one of said seat cushions, and a rigid panel supported on said remaining cushions having a hinged portion bridging the space between the remaining seat cushion and the lone back cushion to support said mattress over the dressing space and movable with the mattress to a vertical position to expose said dressing space, said rigid panel having a hinged flap engageable between one of said horizontal back cushions and a partition to prevent longitudinal displacement of the panel, and hinged flaps on said panel engageable with the side wall and a seat end to prevent lateral displacement of the panel.
- 75 11. In a railway car having a section defined by partitions, confronting seats in the section each having a back cushion and a seat cushion convertible jointly to provide a mattress support, a mattress on said cushions, dressing space in said section formed by removal of one of said seat cushions, and a rigid panel supported on

5 said remaining cushions having a hinged portion bridging the space between the remaining seat cushion and the lone back cushion to support said mattress and movable with the mattress to a vertical position to expose said dressing space, means for holding said mattress and hinged portion of the panel in said vertical position, and means for detachably securing said holding means to one of said partitions.

10 12. In a railway car having a section, confronting seats in the section each having a back cushion and a seat cushion convertible jointly to form a mattress support, a mattress on said cushions, dressing space in said section formed by removal of one of said seat cushions, and a rigid panel supported on said remaining cushions having a hinged portion supporting said mattress over said dressing space and movable with said mattress to a position to expose said dressing space, and 15 a portable washstand detachably secured to a wall of said section in said dressing space.

15 13. In a railway car having a section, confronting seats in the section each having a back cushion and a seat cushion convertible jointly to form a mattress support, a mattress on said cushions, dressing space in said section formed by removal of one of said seat cushions, and a rigid panel supported on said remaining cushions 20 having a hinged portion supporting said mattress over said dressing space and movable with said mattress to a position to expose the dressing space, a baggage shelf supported on said headrest cushion in the vertical position thereof, removable means securing said shelf to the headrest cushion, and adjustable means connecting 25 the shelf with said curtain rod.

having a hinged portion supporting said mattress over said dressing space and movable with said mattress to a position to expose said dressing space, a portable washstand detachably secured to a wall of said section in position to be 5 used in said dressing space, and portable hot and cold water supply means carried in a common supporting member.

14. In a railway car having a section defined by partitions, a curtain-supporting rod extending 10 between said partitions, confronting seats in the section each having a headrest cushion adjustable to a vertical position and back and seat cushions respectively convertible jointly to form a mattress support, a mattress on said converted 15 seat cushions, dressing space in said section formed by removal of one of said seat cushions and a rigid panel supported on said remaining cushions having a hinged portion supporting said mattress over said dressing space and movable 20 with said mattress to a position to expose the dressing space, a baggage shelf supported on said headrest cushion in the vertical position thereof, removable means securing said shelf to the headrest cushion, and adjustable means connecting 25 the shelf with said curtain rod.

DAVID A. CRAWFORD.
